DESIGN FOR A SHOE

Edwin W. McCain, St. Louis, Mo.

Application June 21, 1937, Serial No. 69,944

Term of patent 3½ years

To all whom it may concern:

Be it known that I, Edwin W. McCain, a citizen of the United States of America, residing in St. Louis, and State of Missouri, have invented a new, original, and ornamental Design for a Shoe, of which the following is a specification, reference being had to the accompanying drawing, forming part thereof,

Fig. 1 is a plan view of a shoe showing my new design.

Fig. 2 is a side elevational view thereof.

The characteristic feature of my design resides in a shoe of the type shown having a high pointed vamp with a bow lacing near the top thereof in combination with the upper portion of the vamp being joined to the forward portion of the upper quarter by means of lacing, approximately three quarters of the shoe being of a color contrasting to the remaining part thereof.

I claim:

The ornamental design for a shoe substantially as shown and described.

EDWIN W. McCAIN.
